UNITED STATES PATENT OFFICE

PAUL R. ZINSER, OF CINCINNATI, OHIO, ASSIGNOR TO THE QUEEN CITY SILVER COMPANY, OF CINCINNATI, OHIO, A CORPORATION.

DESIGN FOR A CANDELABRUM.

No. 39,404.

Specification for Design.

Patented July 7, 1908.

Application filed February 17, 1908. Serial No. 416,426. Term of patent 7 years.

To all whom it may concern:

Be it known that I, PAUL R. ZINSER, a subject of the Emperor of Germany, residing at Cincinnati, in the county of Hamilton and State of Ohio, have invented a new, original, and ornamental Design for a Candelabrum, of which the following is a specification, reference being had to the accompanying drawing, forming part thereof.

The figure is a front elevation of a candelabrum, showing my new design.

I claim:

The ornamental design for a candelabrum, as shown.

PAUL R. ZINSER.
